UNITED STATES PATENT OFFICE.

CHARLES P. HOWE, OF WALTERS, OKLAHOMA.

WORKING BARREL.

Application filed September 20, 1924. Serial No. 738,934.

To all whom it may concern:

Be it known that I, CHARLES P. HOWE, a citizen of the United States, residing at Walters, in the county of Cotton and State 5 of Oklahoma, have invented certain new and useful Improvements in Working Barrels, of which the following is a specification.

This invention relates to working barrels especially adapted to be used in oil wells, and it consists in the novel features hereinafter described and claimed.

An object of the invention is to provide a working barrel or pump of simple and durable arrangement having its parts and features so assembled and associated that gas, oil, and other fluids may be readily pumped out of the well, without the use of tubing, other than the regular casing in the 20 well.

In the accompanying drawing:

Figure 1 is a vertical sectional view of the working barrel.

Figure 2 is a transverse sectional view 25 thereof, cut on the line 2—2 of Figure 1.

As illustrated in the accompanying drawing the well casing is indicated at 1. The working barrel comprises a cylindrical fitting 2, provided at one end with a nipple portion 3, and at its opposite end with a nipple portion 4. The nipple portion 4 is of greater diameter than the nipple portion 3. Passageways 5 pass longitudinally through the fitting 2 and communicate at 30 their lower ends with the interior of the nipple 4. The said passages 5 are disposed exteriorly of the nipple 3, and a valve member 6 is slidably mounted upon the nipple 3 and the same is adapted to close over the upper ends of the passageways 5. The fitting 2 is further provided with longitudinally disposed openings 7, which are located exteriorly of the nipple 4. A valve member 8 is slidably mounted upon the nipple 4 and is adapted to close against the lower 35 ends of the openings 7. A nut 9 is screwed upon the lower end of the nipple 4 and is adapted to retain the valve members in position upon the nipple. The fitting 2 is provided at its outer side with a soft rubber sleeve 10, adapted to fit snugly against the interior surface of the well casing 1. A cage 11 is mounted upon the upper end of the fitting 2 and is provided with a 40 number of openings 12. A cylinder 13 is connected at its upper end with the nipple 45

4, and carries at its lower end a ball valve 14. A valve controlled plunger 15 is located in the cylinder 13, and is connected with the stem 16, which extends through the center of the fitting 2, through the nipple 3, and through the center of the cage 11. A perforated liner 17 is located in the casing 1, at the lower portion of the well. 60

When the pump is lowered into the well, 65 the valve 8 rests upon the upper end of the liner 17, and closes the lower end of the openings 7 and which remains closed, during the operation of the pump. In operation, the stem 16 and plunger 15 are reciprocated in the cylinder 13 by gas, oil, and other fluid drawn into the cylinder 13 and forced upwardly through the passageway 5 and under the valve member 6 of the cage 11. 70

From the cage 11, the fluid passes through the openings 12 and enters the upper portion of the casing and flows out at the top of the well. In order to remove the pump from the well, the fitting 2 and valve 8 80 are lifted off of the upper end of the liner, and thus the valve may pull away from the lower ends of the openings 7, and permit the pump to be lifted out of the well, without lifting the liquid in the well above 85 the pump. In an oil well which does not have gas pressure enough to cause the oil to flow, the hereinbefore described device may be used, and at less expense than by swabbing the well, in order to remove the 90 contents from the upper portion thereof before lifting the pump out of the well. There are wells, in which the production is too large to pump with the regular pumping equipment, and such wells do not have 95 sufficient gas pressure to cause the oil to flow, and for that reason the producer is forced to swab. When the present device is used, it will agitate the contents of the well and keep the contents flowing, and when it is desired to remove the pump from the well, in order to make repairs, it only 100 takes a short time to pull the pump out of the well.

Having thus described the invention, 105 what is claimed is:

1. A working barrel structure comprising a fitting provided at its opposite ends with nipples, one nipple being of greater diameter than the other nipple, a cylinder 110 connected in the larger nipple and having a valve, a plunger slidably mounted in the

cylinder, said fitting being provided with passageways which communicate with the upper end of the cylinder, the valve member slidably mounted upon the smaller nipple and adapted to close the upper ends of said passageways, the said fitting being provided with other passageways located beyond the first mentioned passageways, and a valve member located upon the larger nipple and adapted to be disposed in the lower end of the second mentioned passageways.

2. A working barrel structure comprising a fitting having nipples at its opposite ends, the said fitting being provided with an inner set of passageways communicating at one end with the interior of one nip-

ple, and having their other ends located beyond the exterior side of the other nipple, a valve member slidably mounted upon the last mentioned nipple and adapted to close against the upper end of the said passageways, the said fitting being provided with other passageways located beyond the first mentioned passageways, a valve member slidably mounted upon the lower nipple and adapted to close against the lower end of the second mentioned passageways, a cage mounted upon the fitting, and a packing sleeve located upon the exterior surface of the fitting and below the cage.

In testimony whereof I affix my signature.

CHARLES P. HOWE.
